UNITED STATES PATENT OFFICE.

EDWIN E. SLICK, OF WESTMONT BOROUGH, PENNSYLVANIA.

MINE-CAR BODY.

1,206,151.

Specification of Letters Patent. Patented Nov. 28, 1916.

Original application filed June 9, 1915. Serial No. 32,998. Divided and this application filed November 18, 1915. Serial No. 62,082.

To all whom it may concern:

Be it known that I, EDWIN E. SLICK, a citizen of the United States, and a resident of Westmont Borough, county of Cambria, 5 and State of Pennsylvania, whose post-office address is Johnstown, Pennsylvania, have invented certain new and useful Improvements in Mine-Car Bodies; and I do hereby declare the following to be a full, clear, and 10 exact description of the invention, such as will enable others skilled in the art to which it appertains to make and use the same.

My invention relates to mine or other cars, with particular reference to those made of 15 metal, whereby a light, strong, economical and convenient car body is produced.

One of the objects of my invention is to provide a car body of simple, but at the same time, light form of construction which 20 shall be stiff enough to carry the lading, and one which is so fashioned that a part of the car floor serves as a center sill to transmit buffing and pulling stresses and at the same time gives strength and stiffness to the car 25 floor and the body thereof to enable it to transmit the weight of the lading to the axles and wheels without undue deflection.

My invention also relates to other portions of the construction, as will hereinafter more 30 fully appear.

This application is a division of my application filed June 9, 1915, Serial No. 32,998, entitled Mine car.

Referring now to the annexed sheet of 35 drawings, which forms part of these specifications:—Figure 1 is a top plan view of my mine car; Fig. 2 is a vertical transverse sectional elevation taken on the line II—II of Fig. 1; Fig. 3 illustrates an alternate 40 form of construction for my center sill; and Fig. 4 illustrates still another form of construction of my center sill.

Referring now to the characters of reference on the drawings:—The car floor is 45 indicated as 1, while the center sill comprising a channel, or trough, extending longitudinally of the center of the car floor, is indicated as 2, the sides of the car are indicated as 3, the lower portions substantially 50 vertical and their upper portions flaring outwardly, and 4 are the flanged or beaded top edges of the car sides, which form a neat finish and at the same time stiffen the structure and prevent the deformations which

might otherwise occur, due to impact of 55 lumps of coal, shocks due to knocking shovels or bars thereon, or in fact anything which might distort the edge of the body.

As illustrated in Figs. 1 and 2, the end plates of the car body indicated at 5, are 60 substantially vertical and are provided with flanged bottom and side edges 6, as shown and further provided with notches 7 in the flanges 6 for the purpose of fitting the same 65 around and on the center sill 2, as illustrated. The beaded top edges of the end plates are indicated as 8, while 9 is the axle casing on which the body is mounted and which contains the car axles, which axles and casings are secured to the car body by 70 the straps 10 and the connections as shown. The car wheels are indicated at 11, 12 is the draft gear supporting plate, 13 is the draw bar yoke of the draft rigging, 14 is the draw bar stop plate, 15 are the bent forward ends 75 of the draw bar, 16 are the buffing faces of the bumper, 17 are the flanged sides of the bumper, whereby it is attached by the rivets 18 to the draw bar, 19 is the bumper stop plate. As shown in Fig. 1, the car floor 1 is 80 formed of two pieces of metal with the center sill 2 formed of an inverted channel section 20, having outwardly extending flanges 21 extending longitudinally of the car and connecting the two floor pieces.

Referring now to Fig. 3, showing another form of construction of my center sill: 85 1 are the floor plates, 22 are external angles secured to the floor plates and to the side plates 23, 24 are internal angles secured to 90 the side plates 23 and to the top plate 25, the whole forming a longitudinal box-like structure, extending longitudinally of the center of the car floor.

Referring now to Fig. 4, which illustrates 95 another form of construction of my center sill, the floor plates are indicated as 1, while 22 are the exterior corner angles secured thereto, and to the side plates 23, while between the upper portion of the side plates 23 100 the rolled channel 26 is riveted or bolted to the side plates as shown, this construction forming a box-like projection extending longitudinally of the center of the car body. The upwardly projecting portion of the plate floor 105 of the car on the longitudinal center line thereof forms a trough and girder of rigid construction well adapted to stiffen the floor

and car body to enable it to better carry the load; while at the same time this trough provides a suitable receptacle for the draft rigging, inclosing and guiding the inner ends of the same, and it also forms the center sill and the draft sill of the car, to which the follower plates for the draft rigging are secured. This trough, as shown, may be formed integrally with the plate bottom or may be built up of various plates and shapes as desired. This trough may be inverted or may be upright, as illustrated by the portion 12, in which case all or most of the trough may be below the plate floor.

15 Although I have described and illustrated my invention in considerable detail, I do not wish to be limited to the exact and specified details thereof, as shown and described, but may use such modifications in, substitutions 20 for, or equivalents thereof, as are embraced within the scope of my invention or as pointed out in the claims.

Having thus described my invention, what I claim and desire to secure by Letters Patent is:

1. In a car body, open at the top, a plate floor, a trough extending longitudinally of the car and secured on the plate floor, thereby forming a combined stiffener and center sill.

2. An open top metal car body, comprising floor plates, spaced apart at the longitudinal center of the car, on which plates is an inverted trough, comprised of corner angles, side plates and top plate, secured together 36 and on the floor plates, thereby providing a combined stiffener and center sill.

3. A metallic car body, comprising a plate floor, an inverted trough, composed of external lower angles, side plates secured to 40 said angles, an inverted channel, located and secured between the upper portions of

said side plates, said trough being secured to the floor plates, thereby providing a combined stiffener and center sill.

4. A car body comprising a plate floor, 45 provided with an upwardly projecting and longitudinally extending portion of inverted trough form, thereby forming a stiffener and center sill, sides extending upwardly and integrally from the floor portion, the upper 50 portions of which sides flare outwardly and are provided with a rounded bead on their upper edges.

5. A metallic car body comprising a plate floor, a trough extending longitudinally 55 thereof, side portions extending integrally upwardly from the sides thereof, the upper portions flaring outwardly, in combination with end plates fitted therein and provided with means for securing them to the bottom 60 and side plates aforesaid.

6. A car body comprising a plate floor, provided with a longitudinally extending and upwardly projecting portion of inverted 65 trough form, side portions formed integral with the bottom portions, the upper parts of said sides flaring outwardly, end plates provided with flanges adapted to fit against said bottom and side portions, means for securing the end plates to the bottom and side 70 plates, the intermediate lower portions of said end plates being each provided with a notch and flanges extending from the limits thereof, whereby said end plate fits around the upwardly projecting portion of the bottom 75 and means for securing the same thereto.

In witness whereof I have hereunto set my hand in the presence of two witnesses.

EDWIN E. SLICK.
